(57) **ABSTRACT**

A gaming terminal includes a base game offering a chance of winning a payout according to a predetermined combination; a chance game offering a chance of obtaining a chance flag which qualifies a player to join a special game offering a chance of winning a higher payout than the base game; a terminal storage unit storing the number of chance flags; a terminal display which displays images of the base game, the chance game, and the special game; and a terminal controller. The terminal controller performs the steps of: running the base game and the chance game at the same time; determining and awarding a payout according to a result of the base game; determining and awarding the number of chance flags according to a result of the chance game; accumulatively storing in the terminal storage unit the number of chance flags awarded; awarding a payout determined according to a result of the special game which is run when the number of the chance flags stored in the terminal storage unit equals or surpasses a predetermined number; and awarding a determined special payout, when a value obtained by subtracting a sum of one or more payouts of the special game from a sum of one or more game values inserted from the game value insertion unit equals or surpasses a predetermined value.

**CROSS REFERENCE TO RELATED
APPLICATION**

The present application claims priority from provisional application No. 61/037,121, which was filed on Mar. 17, 2008, the entire disclosure of which is herein incorporated by reference.

BACKGROUND OF THE INVENTION

1. Field of the Invention

The present invention relates to a gaming machine and a playing method thereof.

2. Description of Related Art

Among existing gaming machines, there is a gaming machine including: two or more gaming terminals; terminal controllers respectively provided to the gaming terminal, each of which controllers causes associated one of the gaming terminals to run a game; a center controller for controlling all the terminal controllers. This type of gaming machine is disclosed in specifications of U.S. Pat. No. 5,820,459, U.S. Pat. No. 4,283,709, or U.S. Pat. No. 6,003,013. A terminal controller of a gaming terminal runs a game and awards a payout based on the result of the game independently of another terminal controller of another gaming terminal. The center controller provides various jackpots such as progressive jackpots, mystery jackpots, or the like.

Further, the known gaming machine awards a payout according to a winning (game result) formed as a game is played. For example, as disclosed in U.S. Pat. No. 5,910,048, there is a gaming machine in which game media are reimbursed when loss of the game media reaches a predetermined amount.

An object of the invention is to provide a gaming machine having an entertainment characteristic which is not brought about by the above mentioned prior art, and a playing method thereof.

It is another object of the present invention to provide a gaming machine and a playing method thereof, each realizing a new gaming characteristic by qualifying a player to join a special game through a chance game run at the same time a base game is run.

Still another object of the invention is to provide a gaming machine and a playing method thereof, each increasing player's expectations of refund.

SUMMARY OF THE INVENTION

A gaming terminal of a gaming machine of the present invention is a gaming terminal, including: a base game offering a chance of winning a payout according to a predetermined combination; a chance game offering a chance of obtaining a chance flag which qualifies a player to join a special game offering a chance of winning a higher payout than the base game; a terminal storage unit storing the number of chance flags; a terminal display which displays images of the base game, the chance game, and the special game; a game value insertion unit through which a game value is inserted, the game value being a resource of a payout of the special game, and a terminal controller which performs the steps of: (a1) running the base game and the chance game at the same

2

time; (a2) determining and awarding a payout according to a result of the base game; (a3) determining the number of chance flags according to a result of the chance game, and awarding a resulting number of chance flags; (a4) accumulatively storing in the terminal storage unit the number of chance flags awarded; (a5) awarding a payout determined according to a result of the special game which is run when the number of the chance flags stored in the terminal storage unit equals or surpasses a predetermined number; and (a6) 10 when a value obtained by subtracting the sum of one or more payouts of the special game from a sum of one or more game values inserted from the game value insertion unit equals or surpasses a predetermined value, awarding a determined special payout.

(First Aspect)

According to the structure, the gaming terminal runs the base game, and at the same time runs the chance game offering a chance of obtaining a chance flag which qualifies a player to join the special game offering a chance of winning 15 a higher payout than the base game. Then, the player is awarded a payout according to a result of the base game, and is given zero or more chance flags according to a result of the chance game. Further, the number of chance flags awarded is accumulatively stored in the terminal storage unit of the gaming terminal. When this number equals or surpasses a predetermined number, the special game is run. According to a result of the special game is awarded a payout. This structure allows the player to play the chance game while he/she plays the base game, and allows the player to obtain zero or more chance flags according to a result of the chance game. 20 Accordingly, the player is able to know the result of the chance game while enjoying the base game. This realizes a higher level of gaming characteristic than a gaming machine which independently runs a chance game inside the game terminal where a player is not able to see. Moreover, when a value obtained by subtracting a sum of one or more payouts of the special game from a sum of one or more of game values inserted from the game value insertion unit equals or surpasses a predetermined value, a determined special payout is 25 awarded to a player. Hence, even when the sum of one or more payouts of the special game is small, a special payout may be awarded. Accordingly, it is possible to enable a player to have expectations of a special payout.

A gaming machine of the present invention is a gaming device including: a plurality of the gaming terminals of the gaming machine of the first aspect; a special game offering a chance of winning a higher payout than a base game offering a chance of winning a payout according to a predetermined combination; a center storage unit storing the number of chance flags stored in a terminal storage unit of each of the gaming terminals and a game value, each of the chance flags qualifying a player to join the special game, and the game value being a resource of a payout of the special game; a shared display which displays an image of the special game; and a center controller which performs the steps of: (b1) obtaining one or more chance flags and one or more game values from each of the gaming terminals; (b2) accumulatively storing the number of the chance flags and the number of game values obtained in the center storage unit; (b3) running the special game at a predetermined timing, when the number of chance flags stored in the center storage unit equals or surpasses a predetermined number; and (b4) determining a payout according to a result of the special game. (b5) determining whether a value obtained by subtracting a sum of one or more payouts of the special game from a sum of one or more game values equals or surpasses a predetermined value; and (b6) 40 when the value obtained by subtracting the sum of one or more game values equals or surpasses a predetermined value, awarding a payout determined according to a result of the special game. 45 Accordingly, the player is able to know the result of the special game while enjoying the base game. This realizes a higher level of gaming characteristic than a gaming machine which independently runs a chance game inside the game terminal where a player is not able to see. Moreover, when a value obtained by subtracting a sum of one or more payouts of the special game from a sum of one or more of game values inserted from the game value insertion unit equals or surpasses a predetermined value, a determined special payout is 50 awarded to a player. Hence, even when the sum of one or more payouts of the special game is small, a special payout may be awarded. Accordingly, it is possible to enable a player to have expectations of a special payout.

one or more payouts of the special game from the sum of one or more game values equals or surpasses a predetermined value, determining a special payout.

(Second Aspect)

According to the structure, each of the gaming terminals runs the base game, and at the same time runs the chance game offering a chance of obtaining a chance flag which qualifies a player to join the special game offering a chance of winning a higher payout than the base game. Then, the player is awarded a payout according to a result of the base game, and is given zero or more chance flags according to a result of the chance game. Further, the number of chance flags awarded is accumulatively stored in the center storage unit. When this number equals or surpasses a predetermined number, the center controller runs the special game. The center controller then determines a payout according to a result of the special game. The payout determined by the center controller is awarded to the player by the terminal controller of the gaming terminal. This structure allows the player to play the chance game while he/she plays the base game, and allows the player to obtain zero or more chance flags according to a result of the chance game. Accordingly, the player is able to know the result of the chance game while enjoying the base game. This realizes a higher level of gaming characteristic than a gaming machine which independently runs a chance game inside the game terminal where a player is not able to see. Further, the shared display allows players to play the special game at the same time. With this, the players maybe able to share the feeling while enjoying the special game. The one or more game values obtained from each of the gaming terminals are accumulatively stored in the center storage unit. It is determined whether a value obtained by subtracting a sum of one or more payouts of the special game from a sum of one or more game values equals or surpasses a predetermined value. When the value equals or surpasses a predetermined value, a special payout is determined and awarded to each player through each gaming terminal. Hence, even when a sum of one or more payouts of the special game is small, a special payout may be awarded. Accordingly, it is possible to enable a player to have expectations for a special payout.

The gaming machine of the second aspect may have a count unit that counts the number of special games run. When the special game is run, the center controller may cause the count unit to count the number of special games. When the number of special games reaches a predetermined number, the center controller may determine whether a value obtained by subtracting a sum of one or more payouts of the special game from a sum of one or more game values equals or surpasses a predetermined value.

(Third Aspect)

The according structure causes the count unit to count the number of special games run. When the number of special games reaches a predetermined number, the center controller determines whether a value obtained by subtracting a sum of one or more payouts of the special game from a sum of one or more game values equals or surpasses a predetermined value. Thus, even when the subtracted value often equals or surpasses a predetermined value, a special payout is not awarded to a player unless the predetermined number of special games is run. As a result, it is possible to enable the player to maintain the expectations of the special payout.

In the gaming machine of the second aspect, the center controller may accumulatively store the number of chance flags in the center storage unit for each of the gaming terminals. The center controller may run the special game at a predetermined timing only for the gaming terminal in which the number of chance flags equals or surpasses a predeter-

mined number, and may determine the special payout only for the gaming terminal that runs the special game.

(Fourth Aspect)

In this structure, the special game is run only for the gaming terminal having at least a predetermined number of chance flags. Thus, a player who has won a predetermined number or more of chance flags is able to play the special game, and another player who has not won the predetermined number of chance flags is able to continue the base game. This may be advantageous in that the other player is able to enjoy continuing the base game without his/her pace being interrupted. Further, since the special payout is awarded to a gaming terminal that runs the special game, a merit to join the special game is further increased, so that it is possible to enable the player to concentrate on the game.

In the gaming machine of the second aspect, the controller may accumulatively store the game values and the number of chance flags in the center storage unit for each of the gaming terminals. The center controller may run the special game at a predetermined timing only for the gaming terminal in which the number of chance flags equals or surpasses a predetermined number, and may determine the special payout only for the gaming terminal in which the special game is run and a value obtained by subtracting a sum of one or more payouts of the special game from a sum of one or more game values equals or surpasses a predetermined value.

(Fifth Aspect)

In this structure, the special game is run only for the gaming terminal having at least a predetermined number of chance flags. Thus, a player who has won a predetermined number or more of chance flags is able to play the special game, and another player who has not won the predetermined number of chance flags is able to continue the base game. This may be advantageous in that the other player is able to enjoy continuing the base game without his/her pace being interrupted. In addition, the special payout is awarded to only a player who joins a special game and is awarded a small payout of the special payout even though the player inserts the game value. Hence, a merit to join a special game is further increased, so that unfair feeling between the players may be removed.

The gaming machine of the second aspect may have a count unit that counts the number of special games run. The center controller may accumulatively store the number of chance flags and the game values in the center storage unit for each of the gaming terminals. The center controller may run the special game at a predetermined timing only for the gaming terminal in which the number of chance flags equals or surpasses a predetermined number. When the special game is run, the center controller may cause the count unit to count the number of special games. When the number of special games reaches a predetermined number, the center controller may determine whether a value obtained by subtracting a sum of one or more payouts of the special game from a sum of one or more game values equals or surpasses a predetermined value. The center controller may determine the special payout only for the gaming terminal in which the special game is run and a value obtained by subtracting the sum of one or more payouts of the special game from the sum of the game values equals or surpasses a predetermined value.

(Sixth Aspect)

In this structure, the special game is run only for the gaming terminal having at least a predetermined number of chance flags. Thus, a player who has won a predetermined number or more of chance flags is able to play the special game, and another player who has not won the predetermined number of chance flags is able to continue the base game. This may be advantageous in that the other player is able to enjoy continu-

ing the base game without his/her pace being interrupted. In addition, the special payout is awarded to only a player who joins a special game and is awarded a small payout of the special payout even though the player inserts the game value. Hence, a merit to join a special game is further increased, so that unfair feeling between the players may be removed. Moreover, the count unit counts the number of special games run. When the number reaches a predetermined number, the center controller determines whether a value obtained by subtracting a sum of one or more payouts of the special game from a sum of one or more game values equals or surpasses a predetermined value. Thus, even when the subtracted value often equals or surpasses a predetermined value, a special payout is not awarded to a player unless the predetermined number of special games are run. As a result, it is possible to enable the player to maintain the expectations of the special payout.

A playing method of the present invention is a playing method of a gaming terminal in a gaming machine, which terminal includes a base game offering a chance of winning a payout according to a predetermined combination, a chance game offering a chance of obtaining a chance flag which qualifies a player to join a special game awarding a higher payout than the base game, and a game value insertion unit through which a game value is inserted, the game value being a resource of a payout, the method comprising the steps of: (c1) running the base game and the chance game at the same time; (c2) determining and awarding a payout according to a result of the base game; (c3) determining and awarding the number of chance flags according to a result of the chance game; (c4) awarding a payout determined according to a result of the special game which is run when the number of the chance flags equals or surpasses a predetermined number; and (c5) awarding a determined special payout, when a value obtained by subtracting a sum of one or more payouts of the special game from a sum of one or more game values equals or surpasses a predetermined value.

(Seventh Aspect)

According to the structure, the gaming terminal runs the base game, and at the same time runs the chance game offering a chance of obtaining a chance flag which qualifies a player to join the special game offering a chance of winning a higher payout than the base game. Then, the player is awarded a payout according to a result of the base game, and is given zero or more chance flags according to a result of the chance game. Further, the number of chance flags awarded is accumulatively stored in the terminal storage unit of the gaming terminal. When this number equals or surpasses a predetermined number, the special game is run. According to a result of the special game is awarded a payout. This structure allows the player to play the chance game while he/she plays the base game, and allows the player to obtain zero or more chance flags according to a result of the chance game. Accordingly, the player is able to know the result of the chance game while enjoying the base game. This realizes a higher level of gaming characteristic than a gaming machine which independently runs a chance game inside the game terminal where a player is not able to see. In addition, when a value obtained by subtracting a sum of one or more payouts of the special game from a sum of one or more game values inserted from the game value insertion unit equals or surpasses a predetermined value, a special payout is awarded to a player. Hence, even when a sum of one or more payouts of the special game is small, a special payout may be awarded. Accordingly, it is possible to enable a player to have expectations of a special payout.

BRIEF DESCRIPTION OF THE DRAWINGS

DESCRIPTION OF THE PREFERRED EMBODIMENTS

The following describes an embodiment of a gaming machine and a playing method thereof according to the present invention.

As illustrated in FIG. 1, a gaming terminal 10 of the present invention executes a playing method including the steps of: running a base game and a chance game at the same time; determining and awarding a payout according to a result of the base game; determining and awarding the number of JP chances according to a result of the chance game; awarding a payout determined according to a result of the JP game which is run when the number of the JP chances equals or surpasses a predetermined number; and awarding a rescue payout determined when a value obtained by subtracting a sum of one or more payouts of the JP game from a sum of one or more later-described progressive values based on one or more coins inserted with a later-detailed 1-bet button 26 and a maximum bet button 27 equals or surpasses a predetermined value.

In the present embodiment, the gaming terminal 10 runs a slot game. As shown in FIG. 3, a "base game" in this specification is a game in which base symbols 180 are rearranged in base symbol arrangement areas 150a, and a payout is awarded when a winning is formed according to a relation of the base symbols 180 rearranged. The base game is run under base state. FIG. 3 will be described later.

As shown in FIG. 3, a “chance game” is a game in which JP symbols **180J** are rearranged in JP symbol arrangement areas **150b**, at the same time the base symbols **180** are rearranged in the base game, and a JP chance is awarded when a chance winning is formed according to a relation of the JP symbols **180J** rearranged.

As shown in FIG. 4, a “JP game” is a special game that is run by a later-detailed center controller **200** at the same time in two or more gaming terminals **10** at a predetermined time interval. When this JP game results in a jackpot, a higher payout than a payout awarded from the base game is awarded. The JP game is run at a predetermined timing such as every 30 minutes or the like, and is run only for gaming terminals **10** having obtained at least a predetermined number (e.g. one) of JP chances. In this embodiment, the JP game is a virtual “Fishing Tournament” played by players who have obtained the predetermined number of JP chances. The players playing the JP game are able to see their selected characters fishing on a shared display **203**.

The “arrangement” in this specification means a state where the base symbols **180** and JP symbols **180J** can be visually observed by a player, as shown in FIG. 3. That is, in FIG. 3, the wording means the base symbols **180** displayed in the base symbol arrangement areas **150a**, and the JP symbol **180J** displayed in the JP symbol arrangement areas **150b**. Arranging the base symbols **180** or the JP symbols **180J** again after dismissing them is referred to as “rearranging”.

Further, the “base symbols **180**” are symbols including scatter symbols, which are used in a base game in each of the gaming terminals **10**.

Each of the “scatter symbols” is a symbol whose arrangement could result in a winning irrespective of a pay line L. Appearance of a predetermined number (for example, three) of scatter symbols in a matrix **156** gives an advantage to a player. For example, the advantages includes: a state where coins corresponding to the scatter symbols are paid out, a state where the number of coins to be paid out is added to a credit, a state where a bonus game is started. The pay line L is detailed later.

The “winning” is a result of the base game, by which a payout is awarded. For example, the winning is resulted when a predetermined number (e.g. three) of scatter symbols **156** are arranged in the matrix **156**.

Further, the “JP symbols **180J**” are symbols used in the chance game in the gaming terminal **10**, whose arrangement could result in a winning irrespective of a pay line L. For example, a predetermined number (e.g. three) of JP symbols **180** arranged in the matrix **156** give an advantage to the player. The advantage is a JP chance awarded to the player.

The “chance winning” means that a chance game has resulted in a winning, consequently awarding a JP chance. For example, the chance winning is resulted when a predetermined number (e.g. three) of JP symbols **180J** are arranged in the matrix **156**. Note that the present embodiment deals with a case where one JP chance is awarded to a player when three JP symbols **180** are arranged in the matrix **156**.

The “JP chance” qualifies a player to join the JP game. For each JP chance, a process of determining whether or not a jackpot is awarded is performed once.

The “jackpot” means that the JP game has resulted in a winning, consequently awarding a payout.

The “progressive value” is a game value that is based on one or more coins inserted by a player with the later-described 1-bet button **26** and maximum bet button **27**. One or more progressive values are collected from each of the gaming terminals **10**, and are adopted as a resource of a payout in a JP game.

The “rescue payout” means a rescue pay. In the present embodiment, when the predetermined number of JP games are run (for example, 5 times), if a value obtained by subtracting a sum of one or more payouts of a JP game to be paid out to each of the gaming terminals **10** from a sum of one or more progressive values collected from each of the gaming terminals **10** equals or surpasses a predetermined value (for example, 500 credits), a rescue payout is awarded to the gaming terminals **10**. Further, the rescue payout is awarded only to the gaming terminal **10** in which a JP game is run when the number of JP games reaches a predetermined number and a value obtained by subtracting a sum of one or more payouts of JP games from the one or more progressive values equals or surpasses a predetermined value (for example, 100 credits).

For example, in FIG. 1, when the predetermined number of JP games is run (for example, 5 times), the gaming terminals **10** having terminal numbers A and B are participating in the JP game, and the gaming terminal **10** having a terminal number C is not participating in the JP game. In addition, a payout of the JP game for the terminal number A is high and a payout of the JP game for the terminal number B is low (refer to the left in FIG. 1). In this case, when a value obtained by subtracting a sum of one or more payouts of JP game paid out to the terminal A from a sum of one or more progressive values collected from the terminal number A is less than a predetermined value (for example, 100 credits) and when a value obtained by subtracting a sum of one or more payouts of JP game paid out to the terminal B from a sum of one or more progressive values collected from the terminal number B equals or surpasses a predetermined value, a rescue payout is awarded only to the terminal number B (refer to the right part of FIG. 1). Here, the condition is as follows: a value obtained by subtracting a sum of one or more payouts of JP game paid out to each gaming terminal **10** from a sum of one or more progressive values collected from each gaming terminal **10** by a later-detailed center controller **200** should equal or surpass a predetermined value (for example, 500 credits).

As illustrated in FIG. 2, the gaming machine **1** which executes the above mentioned playing method has the shared display **102**, the center controller **100**, and gaming terminals **10**. Each of the gaming terminals **10** includes a terminal display **101** and a terminal controller **100**.

(Terminal Display **101**)

As illustrated in FIG. 3, the terminal display **101** serving as a display unit has base symbol arrangement areas **150a**, JP symbol arrangement areas **150b**, and a JP chance display area **160**.

Each of the base symbol arrangement areas **150a** is an area of the terminal display **101** where a base symbol **180** is arranged. Each of the JP symbol arrangement areas **150b** is an area of the terminal display **101** where a JP symbol **180J** is arranged. The base symbol arrangement areas **150a** and the JP symbol arrangement areas **150b** are arranged on the terminal display **101** so that a base symbol arrangement area **150a** overlaps a JP symbol arrangement area **150b**. In other words, the base symbols **180** and the JP symbols **180J** are varied or stopped by means of two-layered reels.

The JP chance display area **160** displays therein a total number of JP chances obtained in a chance game. Note that the number of JP chances obtained in each chance game is added to the number of JP chances displayed in the JP chance display area **160**. This number of the JP chances displayed in the JP chance display area **160** is brought back to an initial value such as “zero”, when all the JP chances are consumed by running the JP game.

As illustrated in FIG. 3, the base symbol arrangement areas **150a** and the JP symbol arrangement areas **150b** form the

display windows **151** to **155**. For example, arrangement areas **151a**, **151b**, and **151c** form the display window **151**. Further, the display windows **151** to **155** form the matrix **156**. The matrix **156**, in other words, is a matrix including the plurality of base symbol arrangement areas **150a** and the JP symbol arrangement areas **150b**.

The terminal display **101** may have a mechanical structure adopting a reel device which rotates a reel to arrange the base symbols **180** and the JP symbols **180J**. Alternatively, the terminal display **101** may have an electric structure in which a video reel is displayed as an image, and the base symbols **180** and JP symbols **180J** on the video reel are arranged in the form of an image. Further, the terminal display **101** may adopt a combination of the mechanical structure (reel) and the electrical structure (video reel). Examples of the electrical structure include a liquid crystal display device, a CRT (cathode-ray tube), a plasma display device, or the like. Further, the number of the base symbol arrangement areas **150a** and that of the JP symbol arrangement areas **150b** are not limited. A specific structure of the terminal display **101** will be detailed later.

(Shared Display **203**)

The shared display **203** displays thereon a virtual “Fishing Tournament” in the JP game, as illustrated in FIG. 1. A specific structure of the shared display **203** will be detailed later.

(Terminal Controller **100**)

The terminal controller **100** is structured to perform a first process of running a base game and a chance game at the same time; a second process of determining and awarding a payout according to a result of the base game; a third process of determining and awarding the number of JP chances according to a result of the chance game; a fourth process of awarding a payout determined according to a result of the JP game which is run when the number of the JP chances equals or surpasses a predetermined number; and a fifth process of awarding a rescue payout determined when a value obtained by subtracting a sum of one or more payouts of JP game from a sum of one or more progressive values based on one or more coins inserted with a 1-bet button **26** and a maximum bet button **27** equals or surpasses a predetermined value. In other words, the terminal controller **100** has first to fourth processing units.

The terminal controller **100** is connected to a center controller **200** and is in communication with the center controller **200**.

As illustrated in FIG. 2, the terminal controller **100** is connected to a game starting unit **110**. The game starting unit **110** has a function of outputting a game start signal, in response to an operation by the player. The game start signal output is then input to a later-detailed game running unit **103**.

In response to the game start signal serving as a trigger, the terminal controller **100** outputs a progressive signal to the progressive storage unit **226** of a later mentioned center controller. The progressive signal is a signal indicating a progressive value.

The terminal controller **100** is connected to a BET unit **111**. The BET unit **111** has functions of receiving a bet entered through an operation by the player, and outputting a BET signal. The BET signal output is input to the later-detailed game running unit **103**. The bet unit **111** is a function of the 1-bet button **26** and a maximum bet button **27**.

The terminal controller **100** includes: the game running unit **103**, a symbol storage unit **108**, a JP chance storage unit **109**, a display storage unit **107**, and a display control unit **102**.

The game running unit **103** runs a base game, triggered by the game start signal from the game starting unit **110**. The base game is a game in which base symbols **180** are rear-

ranged in the base symbol arrangement areas **150** of the terminal display **101**. At the same time of running the base game, the game running unit **103** also runs a chance game in which JP symbols **180J** are rearranged in the JP symbol arrangement areas **150b** of the terminal display **101**. Further, the game running unit **103** causes the display control unit **102** to display a JP game, in response to a JP game start signal from the game running unit **224**. Further, the game running unit **103** causes the display control unit **102** to stop displaying the JP game, in response to a JP game end signal from the game running unit **224**. The game running unit **103** then resumes the base game and the chance game.

The symbol storage unit **108** stores the base symbols **180** and JP symbols **180J**. The JP chance storage unit **109** accumulatively stores therein the number of JP chances obtained. The display storage unit **107** stores, as a symbol to be displayed, the base symbols **180** and JP symbols **180J** in the symbol storage unit **108**. The display storage unit **107** stores the number of JP chances in the JP chance storage unit **109**, as the number to be displayed.

The control unit **102** performs setting so that the base symbol arrangement areas **150a** for arranging therein the base symbols **180** overlap the JP symbol arrangement areas **150b** for arranging therein the JP symbols. Further, the display control unit **102** reads out base symbols **180** from the display storage unit **107** and displays the base symbols **180** in the base symbol arrangement areas **150a**, under the control of the game running unit **103**. The display control unit **102** also reads out JP symbols **180J** from the display storage unit **107** and displays the JP symbols **180J** in the JP symbol arrangement areas **150b**, under the control of the game running unit **103**. Further, the display control unit **102** reads out the number of JP chances stored in the display storage unit **107** and displays the number on the JP chance display area **160**, under the control of the game running unit **103**.

The terminal controller **100** includes a base game payout determining unit **105**, a JP chance determining unit **106**, and a payout awarding unit **104**.

The base game payout determining unit **105**, under the control performed by the game running unit **103**, determines whether to award a payout of a base game on the basis of the base symbols **180** rearranged in the base symbol arrangement areas **150a**. In other words, the base game payout determining unit **105** determines whether a base game has resulted in a winning. If it is determined that the base game has resulted in a winning, the base game payout determining unit **105** determines the amount of the payout and outputs a signal to the payout awarding unit **104**.

The JP chance determining unit **106**, under the control of the game running unit **103**, determines whether to award a JP chance on the basis of the JP symbols **180** rearranged in the JP symbol arrangement areas **150b**. In other words, the JP chance determining unit **106** determines whether a chance winning is resulted. When it is determined that the chance winning has resulted in the chance winning, the JP chance determining unit **106** determines the number of the JP chances and outputs a signal to the JP chance storage unit **109**. When awarding a JP chance, the JP chance determining unit **106** outputs a JP chance signal to a later-detailed time recorder **228** of the center controller.

The payout awarding unit **104** awards the payout of the base game determined by the base game payout determining unit **105**. Further, the payout awarding unit **104** awards a payout of a JP game determined by a later-detailed JP game payout determining unit **227** of the center controller, in response to a signal from the JP game payout determining unit **227**. In response to a rescue payout signal received from a

11

rescue payout determining unit 229 of the center controller, the payout awarding unit 104 awards a rescue payout, based on the signal of the rescue payout determining unit 229. Note that the JP game is run when the number of JP chances of a gaming terminal 10, which number is stored in a later-detailed center JP chance storage unit 225 of the center controller, equals or surpasses a predetermined number. Further, an amount of the payout is determined by the JP game payout determining unit 227. Further, when a value obtained by subtracting a sum of one or more payouts of the JP game from a sum of one or more progressive values based on one or more coins inserted with the 1-bet button 26 and the maximum bet button 27 equals or surpasses a predetermined value, a rescue payout is determined by the rescue payout determining unit 229.

Meanwhile, each block of the terminal controller 100 may be realized with hardware or with software as needed.

(Operation of Terminal Controller 100)

The following describes an operation of the terminal controller 100 in the above structure. First, the BET unit 111 receives a BET entered through an operation by a player. Further, a game start signal is output from the game starting unit 110 in response to the player's operation, and a base game and a chance game are run at the same time by the game running unit 103. When both of the games are run at the same time, the display control unit 102, under the control of the game running unit 103, displays base symbols 180 in the base symbol arrangement areas 150a. The display control unit 102 also displays JP symbols 180J in the JP symbol arrangement areas 150b. As described, the terminal controller 100 performs the first process of running a base game and a chance game at the same time, at a predetermined timing.

Further, the base game payout determining unit 105 determines whether the base game has resulted in a winning, based on a relation among the base symbols 180 rearranged in the base symbol arrangement areas 150a. If it is determined that the base game has resulted in a winning, the base game payout determining unit 105 determines an amount of a payout. The payout thus determined is awarded by the payout awarding unit 104. As described, the terminal controller 100 performs the second process of determining and awarding a payout according to a result of the base game.

Further, the JP chance determining unit 106 determines whether the chance game has resulted in a chance winning, on the basis of a relation among the JP symbols 180 rearranged in the JP symbol arrangement areas 150b. If it is determined that the chance game has resulted in the chance winning, the JP chance determining unit 106 determines the number of the JP chances and accumulatively stores the number in the JP chance storage unit 109. Further, the display control unit 102 displays, in the JP chance display area 160, the number of the JP chances stored in the JP chance storage unit 109. As described, the terminal controller 100 performs a third process of determining the number of JP chances according to a result of the chance game, and awarding a resulting number of JP chances.

Further, when a gaming terminal 10 has at least a predetermined number of JP chances, the later-detailed JP game payout determining unit 227 of the center controller determines whether to award a payout of the JP game. In other words, the JP game payout determining unit 227 determines whether or not a jackpot is resulted. If it is determined that a jackpot is resulted, an amount of the payout is determined. The payout of the JP game thus determined is awarded by the payout awarding unit 104. As described, the terminal controller 100 performs the fourth process of awarding a payout determined

12

according to a result of the JP game which is run when the number of the JP chances equals or surpasses a predetermined number.

Further, when a value obtained by subtracting a sum of one or more payouts of the JP game from a sum of one or more progressive values based on one or more coins inserted with the 1-bet button 26 and the maximum bet button 27 having the function of the bet unit 111 equals or surpasses a predetermined value, a rescue payout is determined by the rescue payout determining unit 229. The determined rescue payout is awarded by the payout awarding unit 104. Like this, the terminal controller 100 executes the fifth process of awarding a rescue payout determined when a value obtained by subtracting a sum of one or more payouts of the JP game from a sum of one or more progressive values inserted from the bet unit 111 equals or surpasses a predetermined value.

As is obvious from the above operations, the gaming terminal 10 realizes a playing method including the steps of: running a base game and a chance game at the same time; determining and awarding a payout according to a result of the base game; determining and awarding the number of JP chances according to a result of the chance game; awarding a payout determined according to a result of the JP game which is run when the number of the JP chances equals or surpasses a predetermined number; and awarding a rescue payout determined when a value obtained by subtracting a sum of one or more payouts of the JP game from a sum of one or more progressive values based on one or more coins inserted with the 1-bet button 26 and the maximum bet button 27 equals or surpasses a predetermined value.

In the playing method, the gaming terminal 10 runs a base game, and at the same time, runs a chance game offering a chance of obtaining a JP chance which qualifies a player to join a JP game offering a chance of winning a higher payout than the base game. Then, the player is awarded a payout according to the result of the base game, and is given zero or more chance flags according to the result of the chance game. The player is further awarded a payout according to a result of the JP game which is run when the number of JP chances awarded equals or surpasses a predetermined number. This structure allows a player to play the chance game while he/she plays the base game, and allows the player to obtain zero or more JP chances which are given according to a result of the chance game. Accordingly, the player is able to know the result of the chance game while enjoying the base game. This realizes a higher level of gaming characteristic than a gaming machine which independently runs a chance game inside the gaming terminal 10 where a player is not able to see. In addition, a rescue payout is awarded to a player, when a value obtained by subtracting a sum of one or more payouts of the JP game from a sum of one or more progressive values based on coins inserted with the 1-bet button 26 and the maximum bet button 27 equals or surpasses a predetermined value. Hence, even when a sum of one or more payouts of the JP game is small, a rescue payout may be awarded. Accordingly, it is possible to enable a player to have expectations of a rescue payout.

(Operation of Center Controller 200)

The center controller 200 is structured to execute a sixth process of obtaining JP chances and progressive values from the gaming terminals 10; a seventh process of accumulatively storing the number of JP chances and progressive values obtained in a later-detailed center JP chance storage unit 225 and a progressive storage unit 226 for each of the gaming terminals 10; a eighth process of running a JP game at a predetermined timing only for a gaming terminal 10 in which the number of JP chances stored in the center JP chance

storage unit 225 equals or surpasses a predetermined number; a ninth process of determining a payout according to a result of the JP game; a tenth process of, when the JP game is run, causing a rescue count unit 230 to count the number of JP games run, and when the predetermined number of JP games is run, determining whether a value obtained by subtracting a sum of one or more payouts of the JP game from a sum of one or more progressive values equals or surpasses a predetermined value; and an eleventh process of determining a rescue payout only for a gaming terminal 10 in which the JP game is run and a value obtained by subtracting a sum of one or more payouts of the JP game from a sum of one or more progressive values equals or surpasses a predetermined value. In other words, the center controller 200 includes sixth to eleventh processing units.

As illustrated in FIG. 2, the center controller 200 is connected to terminal controllers 100 respectively provided in gaming terminals 10, and is in communication with each of the terminal controllers 110.

The center controller 200 includes: a JP game running unit 224, a JP game storage unit 223, a JP game screen storage unit 222, and a shared display control unit 221.

The JP game running unit 224 refers to the later-detailed center JP chance storage unit 225 at a predetermined time, so as to determine whether there is a gaming terminal having obtained a JP chance. If there is a gaming terminal 10 having obtained a JP chance, the JP game running unit 224 runs a JP game only for that gaming terminal 10. Further, the JP game running unit 224 outputs a JP game start signal only to a game running unit 103 of the terminal controller 100 provided in the gaming terminal 10 to run the JP game. Further, to end the JP game, the JP game running unit 224 outputs a JP game end signal to the game running unit 103 of the terminal controller 100 provided in the gaming terminal 10 having received the JP game start signal.

In addition, when running the JP game, the JP game running unit 224 outputs a signal to a rescue count unit 230 and outputs a signal to only a terminal controller 100 of the gaming terminal 10 that runs the JP game through the rescue count unit 230. The signal outputted to the rescue count unit 230 from the JP game running unit 224 includes the information about the terminal number of the gaming terminal 10 that runs the JP game, and the like.

JP game storage unit 223 stores therein information regarding the JP game. The JP game screen storage unit 222 stores therein display information based on the information of the JP game stored in the JP game storage unit 223.

The shared display control unit 221, under the control of the JP game running unit 224, reads out the display information in the JP game screen storage unit 222, and causes the shared display 203 to perform displaying based on the display information.

Further, the center controller 200 includes: the time recorder 228, the center JP chance storage unit 225, the JP game payout determining unit 227, a progressive storage unit 226, a rescue count unit 230 and a rescue payout determining unit 229.

The time recorder 228 records the time of receiving a JP chance signal from the JP chance determining unit 106 provided in the terminal controller 100 of the gaming terminal 10, and then outputs a signal to the center JP chance storage unit 225.

The center JP chance storage unit 225 then associates the time having been recorded by the time recorder 228 with the number of chances obtained by a gaming terminal 10, and accumulatively stores therein the time and number.

The JP game payout determining unit 227 determines whether to award a payout of a JP game, under the control of the JP game running unit 224. In other words, the JP game payout determining unit 227 determines whether the JP game has resulted in a jackpot. If the JP game payout determining unit 227 determines that the JP game has resulted in a jackpot, the JP game payout determining unit 227 determines an amount of payout based on a progressive value stored in the progressive storage unit 226. Note that the process of determining whether a JP game has resulted in a jackpot is sequentially performed, in order of time associated with a JP chance, which is stored in the center JP chance storage unit 225. That is, a payout of a JP game is determined, consuming JP chances obtained by one or more gaming terminals 10, in order of the time of obtaining the JP chances. In addition, when a payout of the JP game is determined, the JP game payout determining unit outputs a signal to the payout awarding unit 104 of the terminal controller 100 of the gaming terminal 10 and also outputs a signal including the information about a payout of the JP game for each gaming terminal 10 to the progressive storage unit 226.

The progressive storage unit 226 accumulatively stores a progressive value indicated by a progressive signal received from the terminal controller 100. Further, the progressive storage unit 226 accumulatively stores the payout amount of the JP game determined by the JP game payout determining unit 227 together with the progressive values, for each of the gaming terminals 10.

The rescue count unit 230 counts the number of JP games run, in response to the signal outputted from the JP game running unit 224. When the counter number reaches a predetermined number, the rescue count unit outputs a signal to the rescue payout determining unit 229. In the meantime, the signal outputted to the rescue payout determining unit 229 from the rescue count unit 230 includes the information about the terminal number of the gaming terminal 10 that runs the JP game, or the like.

In response to the signal received from the rescue count unit 230, the rescue payout determining unit 229 refers to a payout amount of the JP game and the progressive value stored in the progressive storage unit 226 for each gaming machine 10, thereby determining whether a value obtained by subtracting a sum of one or more payouts of the JP game from a sum of one or more progressive values equals or surpasses a predetermined value. As a result of the determination, the rescue payout determining unit determines a rescue payout only for the gaming terminal 10 in which a value obtained by subtracting a sum of one or more payouts of the JP game from a sum of one or more progressive values equals or surpasses a predetermined value. Further, the rescue payout determining unit outputs a signal to the payout awarding unit 104 of the terminal controller 100 provided in the gaming terminal 10 for which the rescue payout is determined.

Note that each block of the center controller 200 may be realized with hardware or with software as needed.

(Operation of Center Controller 200)

The following describes an operation of the center controller 200 in the above structure. First, the time recorder 228 receives a JP chance signal from the JP chance determining unit 106 provided in the terminal controller 100 of a gaming terminal 10. That way, the center controller 200 obtains information related to the number of JP chances obtained by the gaming terminal 10. In addition, the progressive storage unit 226 receives a progressive signal from the terminal controller 100 of the gaming terminal 10. That way, the center controller 200 obtains the information about the number of JP chances obtained by the gaming terminal 10 and a progressive value

indicated by the progressive signal. Like this, the center controller **200** performs the sixth process of obtaining JP chances and progressive values from the gaming terminals **10**.

Further, The time recorder **228** records a time upon receiving the information related to the number of the JP chances, and outputs a signal to the center JP chance storage unit **225**. Further, the center JP chance storage unit **225** having received the signal from the time recorder **228** associates the time recorded by the time recorder **228** with the number of JP chances obtained by the gaming terminal **10**, and accumulatively stores therein the time and the number. The progressive storage unit **226** receives the progressive signal and accumulatively stores the progressive values for each of the gaming terminals **10**. Like this, the center controller **200** performs the seventh process of accumulatively storing the number of JP chances and progressive values obtained in the center JP chance storage unit **225** and the progressive storage unit **226**, for each of the gaming terminals **10**.

Meanwhile, the JP game running unit **224** checks the center JP chance storage unit **225** to determine if there is a gaming terminal **10** having obtained a JP chance. When there is a gaming terminal **10** having obtained a JP chance, a JP game is run only for the gaming terminal **10** having obtained the JP chance. As described, the center controller **200** performs the eighth process of running a JP game at a predetermined timing only for a gaming terminal **10** having won at least a predetermined number of JP chances, referring to the number of JP chances stored in the center JP chance storage unit **225**.

Further, the JP game payout determining unit **227** determines whether a JP game has resulted in a jackpot based on the result of the JP game. This operation sequentially consumes at least one of JP chances obtained by a gaming terminal **10**, in order of the times of obtaining the JP chances. If it is determined that a JP game has resulted in a jackpot, the JP game payout determining unit **227** determines a payout according to a progressive value stored in the progressive storage unit **226**. Like this, the center controller **200** performs the ninth process of determining a payout according to a result of the JP game.

Further, the rescue count unit **230** counts the number of JP games run. When the number counted reaches a predetermined number of times, the rescue payout determining unit **229** determines whether a value obtained by subtracting a sum of payouts of the JP game from a sum of progressive values equals or surpasses a predetermined value, only for the gaming terminal **10** in which the JP game is run. Like this, the center controller **200** performs the tenth process of, when the JP game is run, causing a rescue count unit **230** to count the number of JP games run, and when the predetermined number of JP games is run, determining whether a value obtained by subtracting a sum of one or more payouts of the JP game from a sum of one or more progressive values equals or surpasses a predetermined value.

In addition, the rescue payout determining unit **229** determines a rescue payout only for the gaming terminal **10** in which a value obtained by subtracting a sum of payouts of the JP game from a sum of progressive values equals or surpasses a predetermined value. Like this, the center controller **200** performs the eleventh process of determining a rescue payout only for a gaming terminal **10** in which the JP game is run and a value obtained by subtracting a sum of one or more payouts of the JP game from a sum of one or more progressive values equals or surpasses a predetermined value.

With the structure and the operation of the gaming machine **1** described with reference to FIG. 2, one or more gaming terminals **10** run a base game, and at the same time, run a chance game offering a chance of winning a JP chance which

qualifies a player to join a JP game offering a chance of winning a higher payout than the base game. Then, the player is awarded a payout according the result of the base game, and is given zero or more chance flags according to the result of the chance game. The number of JP chances awarded is accumulatively stored in the center JP chance storage unit. When this number equals or surpasses a predetermined number, the center controller **200** runs the JP game. Further, the center controller **200** determines a payout according to a result of the JP game, and the payout determined by the center controller **200** is awarded by the terminal controller **100** of the targeted gaming terminal **10**. This structure allows a player to play the chance game while he/she plays the base game, and allows the player to obtain zero or more JP chances which are given according to a result of the chance game. Accordingly, the player is able to know the result of the chance game while enjoying the base game. This realizes a higher level of gaming characteristic than a gaming machine which independently runs a chance game inside the gaming terminal **10** where a player is not able to see. Further, the shared display **203** allows players to play the special game at the same time. With this, the players may be able to share the feeling while enjoying the special game.

Further, with the structure and the operation of the gaming machine **1** described with reference to FIG. 2, the progressive values obtained from the gaming terminals **10** are accumulatively stored in the progressive storage unit **226**. It is determined whether a value obtained by subtracting a sum of one or more payouts of the JP game from a sum of one or more progressive values stores in the progressive storage unit **226** equals or surpasses a predetermined value. When the value equals or surpasses a predetermined value, a rescue payout is determined and awarded to a player from each gaming terminal **10**. Hence, even when a sum of one or more payouts of the JP game is small, a rescue payout may be awarded. Accordingly, it is possible to enable a player to have expectations of a rescue payout.

Further, with the structure and the operations of the gaming machine **1** described with reference to FIG. 2, the JP game is run only for the gaming terminal **10** having at least a predetermined number of JP chances. Thus, a player who has won a predetermined number or more of JP chances is able to play the JP game, and another player who has not earned the predetermined number of JP chances is able to continue the base game. Thus, it is possible to enable a player who did not obtain the predetermined number of JP chances or more to continuously play the base game without stopping the game and to enjoy the base game.

Further, with the structure and the operation of the gaming machine **1** described with reference to FIG. 2, a rescue payout is awarded to only a player who joins the JP game and is awarded a small payout of the JP game even though the player inserts progressive values. Hence, a merit to join a JP game is further increased, so that unfair feeling between the players may be removed. Moreover, the rescue count unit **230** counts the number of JP games run. When the predetermined number of JP games are run, the rescue payout determining unit **229** determines whether a value obtained by subtracting a sum of one or more payouts of the JP game from a sum of one or more progressive values obtained from the gaming terminals **10** equals or surpasses a predetermined value. Thus, even when the subtracted value often equals or surpasses a predetermined value, a rescue payout is not awarded to a player unless the predetermined number of JP games are run. As a result, it is possible to enable the player to maintain the expectations for the rescue payout.

(Display State of Terminal Display 101)

The following details an exemplary display state of the terminal display 101 during the operations of the gaming machine 1 and the playing method thereof. Note that the following example deals with a case where the terminal display 101 adopts a video reel and arranges symbols on a video reel in the form of an image, as illustrated in FIG. 3.

As illustrated in FIG. 3, a matrix 156 is in the center of the terminal display 101. The matrix 156 includes a symbol column having symbols 180 and a symbol column having JP symbols 180J, which columns overlap each other. Further display windows 151 to 155 are each divided into an upper stage 151a, a middle stage 151b, and a lower stage 151c. The base symbols 180 and the JP symbols 180J are stopped (arranged) in each of the stages 151a to 151c so that a base symbol 180 overlaps a JP symbol 180J. For example, in FIG. 3, a "Clownfish" which is a base symbol 180 is stopped in a base symbol arrangement area 150 in the upper stage 151a of the display window 151, and a "GET" which is a JP symbol 180J is stopped in the JP symbol arrangement area 150b so as to overlap the "Clownfish". Further, a "Coelacanth" is stopped in the base symbol arrangement area 150a in the middle stage 151b of the display window 151, and no symbol is stopped in the JP symbol arrangement area 150b overlapping the "Coelacanth". Further, a "Clownfish" is stopped in the base symbol arrangement area 150a in the bottom stage 151c of the display window 151, and no symbol is stopped in the JP symbol arrangement area 150b overlapping the "Clownfish". In short, the matrix 156 is a symbol matrix including five columns/three rows. The matrix 156 however is not limited to the one with the five-columns/three-rows.

Further, the JP chance display area 160 is disposed upper right of the terminal display 101, and displays thereon the number of JP chances having obtained. For example, in FIG. 3, the number of JP chances is "1". As such, a player is able to join the JP game only once to be subjected to a process of determining whether a payout is awarded.

The base symbols 180 and the JP symbols 180J are arranged so that a base symbol overlaps a JP symbol 180J as illustrated in the upper part of FIG. 3, when the base game and the chance game are run at the same time. A player usually plays a game, viewing a screen displayed according to the display state illustrated in the upper part of the figure.

At the lower left of the figure is provided an illustration of displayed elements related to a base game. In the base game are arranged base symbols 180. In the case of FIG. 3, the matrix 156 includes a predetermined number (three in the present embodiment) or more of "Coelacanth" each of which is a scatter symbol of the base game in the present embodiment. Thus, the base game has resulted in a winning in the case of FIG. 3.

At the lower right of the figure is provided an illustration of displayed elements related to a chance game. In a chance game are arranged JP symbols 180J. In the case of FIG. 3, the matrix 156 presents a predetermined number (three in the present embodiment) or more of "GET". The chance game in this case therefore has resulted in a winning, and "1" is added to the number of JP chance. As the result, the JP chance display area 160 displays "2".

This displaying state allows the player to play the chance game while he/she plays the base game, and allows the player to obtain zero or more JP chances according to a result of the chance game. Accordingly, the player is able to know the result of the chance game while enjoying the base game. This realizes a higher level of gaming characteristic than a gaming machine which independently runs a chance game inside the gaming terminal 10 where a player is not able to see. Further,

the number of JP chances obtained in a chance game is displayed in the JP chance display area 160 of the terminal display 101 during a base game. This may allow the player to play the base game while letting him/her know the number of JP chances. Thus, the above structure may motivate the player to continuously play games for a longer period of time.

(Display State of Shared Display 203)

The following details an exemplary display state of the shared display 203 during the operations of the gaming machine 1 and the playing method thereof. As illustrated in FIG. 4, JP game is viewed on the shared display 203 by players of gaming terminals 10 which are respectively given a terminal number A, a terminal number B, a terminal number C, and a terminal number D. JP game is run at a predetermined timing. The JP game however is not run for a gaming terminal 10 having no JP chances. For example, in the case of FIG. 4, a JP game is not run in the gaming terminal 10 with the terminal number C, and a base game is displayed on the terminal display 101 of the terminal number C. On the other hand, the JP game is run for other three gaming terminals 10 with the terminal numbers A, B, and D. Further, in FIG. 4, the gaming terminal 10 with the terminal number B has won a jackpot, and that win is displayed on the shared display 203.

Further, the shared display 203 allows players to play the special game at the same time. With this, the players may be able to share the feeling while enjoying the special game. Further, the JP game is run only for the gaming terminal 10 having at least a predetermined number of JP chances. Thus, a player who has won a predetermined number or more of JP chances is able to play the JP game, and another player who has not earned the predetermined number of JP chances is able to continue the base game. This may be advantageous in that the other player is able to enjoy continuing the base game without his/her pace being interrupted.

(Symbol, Combination, or the Like)

A terminal display 101 has a matrix 156 including symbol columns each having twenty two base symbols 180 as illustrated in FIG. 5. To each of the symbols constituting the columns is given one of code numbers 0 to 21. Each of the symbol columns has a combination of symbols including "Angelfish", "Clownfish", "7", "Tuna", "Coelacanth", and "BONUS".

Of the symbols in the symbol columns, the display windows 151 to 155 each displays (arranges) three successive symbols. The symbols arranged in the upper stage 151a, the middle stage 151b, and the lower stage 151c form a symbol matrix having five columns and three rows. When a BET button and a start button are sequentially pressed in this order to start a game, symbols constituting the symbol matrix start to scroll. This scrolling of the symbols stops (rearrangement) after a predetermined period from the beginning of the scrolling.

Further, for each symbol, a predetermined scatter symbol is determined in advance. Scatter symbols are such symbols that a player is put in an advantageous position when a predetermined number or more of them are displayed in the matrix 156. For example, the advantages includes: a state where coins corresponding to the scatter symbols are paid out, a state where the number of coins to be paid out is added to a credit, a state where a bonus game is started.

To be more specific, when three or more symbols of "BONUS" are rearranged in the matrix 156, a bonus is triggered and a gaming state shifts from a base game to a bonus game. Further, when four or more "BONUS" are displayed in the matrix 156, twenty coins (game medium) are paid out for one bet.

Here, a bonus game is a gaming state which provides a larger advantage than a base game. In this embodiment, the bonus game is a free game. The free game is a game allowing a player to play a game a predetermined number of times without betting a coin. No particular limitation is put on the bonus game, as long as it is a gaming state advantageous to the player, that is, it is more advantageous than the base game. For example, the bonus game may include a state where more game values are obtainable than in the base game, a state where a game medium is obtainable with higher probability than in the base game, a state where a game medium is less consumed than in the base game, and the like. Specifically, a free game, a second game, a feature game, and the like may be mentioned as examples of the bonus game.

(Mechanical Structure of Gaming Machine 1)

Next, the following describes a specific example of mechanical and electrical structures of the gaming machine 1 thus structured.

A gaming machine 1 is placed in a gaming facility such as a casino. This gaming machine 1 runs a unit game which involves a game medium. The game medium is a coin, bill, or a value in the form of electronic information. However, the game medium in the present invention is not particularly limited. For example, a medal, token, electronic money, ticket or the like are also possible. Further, the ticket is not particularly limited and may be a later-detailed ticket with a barcode or the like ticket.

As illustrated in FIG. 6, the gaming machine 1 includes: gaming terminals 10 which run a base game independently from each other; a center controller 200 connected to the gaming terminals 10, which is in communication with the gaming terminals 10 and runs a JP game; a shared display 203 which displays thereon an effect image related to the JP game; a rail 271 which supports the shared display 203 and allows the shared display 203 to move to a position immediately above one of the gaming terminals 10; and a not-illustrated drive motor 270 which causes the shared display 203 to move along the rail 271.

As illustrated in FIG. 7, the gaming terminal 10 includes: a cabinet 11, a top box 12 provided above the cabinet 11, and a main door 13 provided on the front surface of the cabinet 11. The main door 13 has a lower image display panel 16. The lower image display panel 16 has a transparent liquid crystal panel for displaying various information. The lower image display panel 16 displays display windows 151 to 155 (matrix 156) for arranging therein base symbols 180. Further, the lower image display panel 16 displays as needed various information and effect images related to a game. Further, at the upper right of the lower image display panel 16 is displayed a JP chance display area 160.

The present embodiment deals with a case where the lower image display panel 16 electrically displays base symbols 180 and JP symbols 180J arranged in five rows/three columns so that a base symbol 180 overlaps a JP symbol 180J. However, the present invention is not limited to this.

The lower image display panel 16 displays a single activated pay line L. The "pay line L" is used for determining a combination of the base symbols 180. That is, when base symbols 180 are rearranged on and out of the pay line L, a combination is determined for only the base symbols 180 rearranged on the pay line. When the combination is recognized as a winning combination. There is performed a process such as awarding of a coin according to the winning combination or the like. Note that the number of pay lines L may be two or more. When the number of pay lines L is two or more,

the number of pay lines L activated may be determined according to a predetermined condition, such as the number of coins placed as a BET.

Note that the lower image display panel 16 may have a credit value indicator and a payout value indicator. The credit value indicator displays a total value (hereinafter also referred to as total credit value) which a gaming terminal 10 can pay out to a player. When symbols stopped along a pay line L form a winning combination, the payout value indicator displays the number of coins to be paid out.

Further, scatter symbols may be adopted, and the number of coins to be paid out may be determined, according to the number of scatter symbols displayed on the matrix 156. Note that the pay line L does not necessarily have to be displayed.

Below the lower image display panel 16 provided are a control panel 20, a coin insertion slot 21, and a bill validator 22. The control panel 20 is provided with various buttons 23 to 27. These buttons 23 to 27 allow a player to input instructions related to a game played by the player. Through the coin insertion slot 21, a coin is received in the cabinet 11.

The control panel 20 includes: a spin button 23, a change button 24, a cashout button 25, a 1-BET button 26, and a maximum BET button 27. The spin button 23 is for inputting an instruction to start symbol scrolling. The change button 24 is used to ask a staff person in the gaming facility for exchange of money. The cash out button 25 is for inputting an instruction to pay out coins corresponding to the total credit-value into the coin tray 18, via a coin payout opening 19.

The 1-BET button 26 is used for betting two coins out of those corresponding to the total credit value. The maximum BET button 27 is used for betting, out of those corresponding to the total credit value, a maximum number of coins (e.g., fifty coins) which can be bet in one game.

Of the two coins bet by pressing of the 1-BET button 26 once, one is placed as a bet for a base game, and the other serves as a source of a payout of a JP game. In short, one of two coins is a progressive value and is used for a resource of the JP game. In short, the player is making a bet for the JP game while making a bet for the base game.

The bill validator 22 validates whether bill is genuine or not and receives the genuine bill into the cabinet 11. Note that the bill validator 22 is capable of reading a barcode attached to the later-detailed ticket 39 having a barcode (hereinafter simply referred to as ticket 39). When the bill validator 22 reads the ticket 39, it outputs to the main CPU 41 a read signal representing information having read from the barcode.

On the lower front surface of the main door 13, that is, below the control panel 20, a berry glass 34 is provided. On the belly glass 34, a character of a gaming terminal 10 or the like is drawn. On the front surface of top box 12 is provided an upper image display panel 33. The upper image display panel 33 has a liquid crystal panel and displays an effect image, introduction to the game, rules of the game, or the like.

Further, the top box 12 has a speaker 29 for performing an audio output and a lamp 30. Below the upper image display panel 33 are provided a ticket printer 35, a card reader 36, a data display 37, and a keypad 38. The ticket printer 35 prints, on to a ticket, a barcode having encoded data containing credit-value, date and time, identification number of a gaming terminal 10 or the like, thereby issuing a ticket 39 having a barcode attached thereto. A player can play a game in another gaming terminal 10 with the ticket 39 having the barcode, or exchange the ticket 39 having the barcode with bill or the like at a change booth or the like of the game arcade.

The card reader 36 reads/writes data from/into a smart card. The smart card is carried by a player, and stores therein

data for identifying the player, data relating to a history of games played by the player, or the like.

The data display 37 includes a fluorescent display or the like, and displays the data read by the card reader 36 and the data input by the player through the keypad 38. The keypad 38 is for entering instructions or data relating to issuing of a ticket or the like.

(JP Chance Data Table)

The center controller 200 of the gaming machine 1 has a JP chance data table as illustrated in FIG. 9. As illustrated in FIG. 8, the JP chance data table stores information pieces obtained by the center controller 200. Each of the information pieces includes the number of JP chances obtained in a chance game run in a gaming terminal 10 and a time of obtaining the JP chances. In the present embodiment, the table indicates that a gaming terminal 10 with the terminal number A has obtained one JP chance for the first time at 11:00, and two JP chances for the second time at 13:00. The table further indicates that that a gaming terminal 10 with the terminal number A has obtained one JP chance for the first time at 12:00, another JP chance for the second time at 15:00, and two JP chances for the third time at 15:30. The center controller 200 administers the number of JP chances and time of obtaining the JP chances, for each of the gaming terminal 10, thereby allowing the JP chances to be consumed at the time of determining a payout in order of obtaining the JP chances. Thus, by determining payouts for players in such a manner that a player who is entitled to a payout awarding earlier than another receives a higher payout, it may be possible to keep the enthusiasm of players to obtain JP chances earlier than the others.

(Payout History Data Table)

The center controller 200 of the gaming machine 1 has a payout history data table as illustrated in FIG. 10. The payout history data table stores therein "accumulated JP payout amount," "accumulatively inserted bet amount" and "subtraction amount" for each of the gaming terminals 10.

The "accumulated JP payout amount" is obtained by accumulating one or more payouts of JP game awarded to each of the gaming terminals 10. The "accumulatively inserted bet amount" is a value of coins equivalent to the accumulated progressive values, i.e., a part of the value of coins inserted by a player with the 1-bet button 26 and the maximum bet button 27, which is used as a resource of JP game. The "subtraction amount" is obtained by subtracting the accumulated JP payout amount from the accumulatively inserted bet amount.

In addition, the payout history data table stores therein a sum of the "accumulated JP payout amounts," a sum of the "accumulatively inserted bet amounts" and a sum of the "subtraction amounts" in all the gaming terminals 10. In the present embodiment, the payout history data table stores therein "35" credits of the accumulated JP payout amount, "195" credits of the accumulatively inserted bet amount and "160" credits of the subtraction amounts of both amount, for the terminal number A. Likewise, also for the terminal numbers B, C, and D, the payout history data table stores therein the amounts of each item. Regarding the subtraction amount, the payout history data table stores therein "85" credits for the terminal number B, "180" credits for the terminal number C and "95" credits for the terminal number D. In addition, the sums of each item in all the gaming terminals 10 are "180 credits" of the accumulated JP payout amounts, "700" credits of the accumulatively inserted bet amounts and "520" credits of the subtraction amounts.

For example, if it is set that a rescue payout is awarded when a sum of the subtraction amounts of all the gaming terminals 10 equals or surpasses 500 credits, the rescue payout is awarded to each of the gaming terminals 10. In addition

to the above, for example, if it is set that a rescue payout is awarded only to the gaming terminal 10 in which the subtraction amount equals or surpasses 100 credits, the rescue payout is awarded only to the gaming terminals 10 of terminals numbers A and C.

(Electrical Structure of Gaming Machine 1)

FIGS. 11 and 12 are block diagrams each illustrating an electrical structure of the entire gaming machine 1.

(Electrical Structure of Gaming Terminal 10)

FIG. 11 is a block diagram illustrating an electrical structure of the gaming terminal 10. As illustrated in FIG. 11, the cabinet 11 includes a control unit having a terminal controller 100. As shown in FIG. 11, the control unit includes a motherboard 40, a main body PCB (Printed Circuit Board) 60, a gaming board 50, a door PCB 80, various switches, sensors, or the like.

The gaming board 50 is provided with a CPU (Central Processing Unit) 51, a ROM 55, a boot ROM 52, a card slot 53S corresponding to a memory card 53, and an IC socket 54S corresponding to a GAL (Generic Array Logic) 54. The CPU 51, the ROM 55, and the boot ROM 52 are connected to one another through an internal bus.

The memory card 53 stores therein a game program and a game system program. The game program contains a stop symbol determining program. The stop symbol determining program is a program for determining: base symbols 180 (code numbers corresponding to the symbols) to be stopped in the base symbol arrangement area 150a; and JP symbols 180J (code numbers corresponding to the symbols) to be stopped in the JP symbol arrangement area 150b. This stop symbol determining program contains sets of symbol weighting data respectively corresponding to various payout rates (e.g., 80%, 84%, 88%). Each set of the symbol weighting data indicates, for each of the display windows 151 to 155, a code number of each symbol and at least one random numerical value allotted to the code number. The numerical value is a value within a predetermined range of 0 to 256 for example.

The payout rate is determined based on payout rate setting data output from the GAL 54. Based on a set of the symbol weighting data corresponding to the payout rate determined, a symbol to be stopped is determined.

The memory card 53 stores therein various types of data for use in the game programs and the game system programs. For example, the memory card 53 stores a table listing combinations of a base symbol 180 to be displayed on the display windows 151 to 155 of FIG. 1 and an associated range of random numerical values. This data is transferred to the RAM 43 of the motherboard 40, at the time of running a game programs.

The card slot 53S is structured so as to allow the memory card 53 to be attached/detached to/from the card slot 53S. This card slot 53S is connected to the motherboard 40 through an IDE bus. Thus, the type and content of a game run by a gaming terminal 10 can be modified by detaching the memory card 53 from the card slot 53S, write a different game program and a different game system program into the memory card 53, and inserting the memory card 53 back into the card slot 53S.

Each of the game programs includes a program related to the progress of the game and/or a program for causing a transition to a bonus game. Each of the game programs includes image data and audio data output during the game.

The GAL 54 has input and output ports. When the GAL 54 receives data via the input port, it outputs data corresponding to the input data from its output port. This data from the output port is the payout rate setting data described above.

IC socket 54S is structured so as to allow the GAL 54 to be attached/detached to/from the IC socket 54S. The IC socket 54S is connected to the motherboard 40, via a PCI bus. Thus, the payout rate setting data to be output from GAL 54 can be modified by: detaching the GAL 54 from the IC socket 54S, overwriting the program stored in the GAL 54, and attaching the GAL 54 back to the IC socket 54S.

The CPU 51, the ROM 55 and the boot ROM 52 connected through an internal bus are connected to the motherboard 40 through the PCI bus. The PCI bus communicates signals between the motherboard 40 and the gaming board 50 and supplies power from the motherboard 40 to the gaming board 50. The ROM 55 stores country identification information and an authentication program. The boot ROM 52 stores a preliminary authentication program and a program (boot code) for enabling the CPU 51 to run the preliminary authentication program.

The authentication program is a program (falsification check program) for authenticating the game program and the game system program. The authentication program is a program for confirming and verifying that the game program and the game system program are not falsified. In other words, the authentication program is described in accordance with a procedure for authenticating the game program and the game system program. The preliminary authentication program is a program for authenticating the authentication program. The preliminary authentication program is described in accordance with a procedure for verifying that the authentication program to be authenticated is not falsified. In short, the preliminary authentication program authenticates the authentication program.

The motherboard 40 is provided with a main CPU 41 (terminal controller 100), a ROM (Read Only Memory) 42, a RAM (Random Access Memory) 43 and a communication interface 44.

The main CPU 41 serves as a terminal controller 100 and has a function of controlling the entire gaming terminal 10. In particular, the main CPU 41 controls the following operations: an operation of outputting a signal instructing variable-displaying of symbols 180 to the graphic board 68, which is performed in response to pressing of the spin button 23 after betting of credit; an operation of determining symbols 180 to be stopped after the variable-displaying of symbols 180; and an operation of stopping the symbols 180 thus determined in the display window 151 to 155.

In other words, the main CPU 41 serves as an arrangement controller which arranges symbols to form a new symbol matrix through scrolling of symbols displayed on the lower image display panel 16. This main CPU 41 therefore determines symbols to be arranged in a symbol matrix by selecting symbols to be arranged from various kinds of symbols. Then, the main CPU 41 executes arrangement control to stop scrolling of the symbols to present the symbols thus determined.

The main CPU 41 serves as a terminal controller 100 which performs a first process of running a base game and a chance game at the same time; a second process of determining and awarding a payout according to a result of the base game; a third process of determining and awarding the number of JP chances according to a result of the chance game; a fourth process of awarding a payout determined according to a result of the JP game which is run when the number of the JP chances equals or surpasses a predetermined number; and a fifth process of awarding a rescue payout determined when a value obtained by subtracting a sum of payouts of JP game from a sum of progressive values based on coins inserted from a 1-bet button 26 and a maximum bet button 27 equals or surpasses a predetermined value. The main CPU 41 serves as:

the game running unit 103 of FIG. 2, the display control unit 102, the base game payout determining unit 105, the JP chance determining unit 106, and the payout awarding unit 104.

5 The ROM 42 stores a program such as BIOS (Basic Input/Output System) run by the main CPU 41, and permanently-used data. When the BIOS is run by the main CPU 41, each of peripheral devices is initialized and the game program and the game system program stored in the memory card 53 are read out through the gaming board 50.

10 The RAM 43 stores data or a program used for the main CPU 41 to perform a process. For example, RAM 43 has the symbol storage unit 108 of FIG. 2, the JP chance storage unit 109, and the display storage unit 107, in the form of data area. 15 Then, in the data area of the symbol storage unit 108 are stored base symbols 180 and JP symbols 180J. In the data area of the JP chance storage unit 109 is stored an accumulated total of JP chances obtained. In the data area of the display storage unit 107 are stored base symbols 180 and JP symbols 180 to be displayed, and the number of the JP chances to be displayed.

20 The communication interface 44 is provided to communicate with a host computer and the like equipped in the gaming facility, through the network (communication line). The communication interface 44 is also for communicating with the center controller 200 through a communication line. Further, a main body PCB (Printed Circuit Board) 60 and a door PCB 80 are connected to the motherboard 40, through a USB (Universal Serial Bus). Further, the motherboard 40 is connected to a power unit 45. The power unit 45 supplies power to the motherboard 40 to boot the main CPU 41 thereof. Meanwhile, the power unit 45 supplies power to the gaming board 50 through the PCI bus to boot the CPU 51 thereof.

25 The main body PCB 60 and door PCB 80 are connected to various devices or units which generate signals to be input to the main CPU 41, and various devices or units whose operations are controlled by signals from the main CPU 41. Based on a signal input to the main CPU 41, the main CPU 41 runs the game program and the game system program stored in the RAM 43, to perform an arithmetic process. Then, the CPU 41 stores the result of the arithmetic process in the RAM 43, or transmits a control signal to the various devices and units to control them based on the result.

30 The main body PCB 60 is connected with a lamp 30, a hopper 66, a coin sensor 67, a graphic board 68, a speaker 29, a bill validator 22, a ticket printer 35, a card reader 36, a key switch 38S, and a data display 37.

35 The lamp 30 is turned on/off on the basis of a control signal from the main CPU 41.

The hopper 66 is mounted in the cabinet 11 and pays out a predetermined number of coins from a coin outlet 19 to the coin tray 18, based on a control signal from the main CPU 41. The coin sensor 67 is provided inside the coin outlet 19, and 40 outputs a signal to be input to the main CPU 41 upon sensing that a predetermined number of coins have been delivered from the coin outlet 19.

45 The graphic board 68 controls image displaying of upper image display panel 33 and the lower image display panel 16, based on a control signal from the main CPU 41. Further, the graphic board 68 is provided with a VDP (Video Display Processor) for generating image data on the basis of a control signal from the main CPU 41, a video RAM for temporarily storing the image data generated by the VDP, or the like. Note 50 that image data used at the time of generating the image data by the VDP is in a game program which is read out from the memory card 53 and stored in the RAM 43.

The bill validator 22 reads an image on the bill and takes only those recognized as to be genuine into the cabinet 11. When taking in a genuine bill, the bill validator 22 outputs an input signal indicating the value of the bill to the main CPU 41. The main CPU 41 stores into the RAM 43 a credit-value corresponding to the value of the bill indicated by the signal.

The ticket printer 35 prints a barcode on to a ticket to issue a ticket 39 having the barcode. The barcode contains encoded data such as credit-value stored in the RAM 43, date and time, identification number of the gaming terminal 10, or the like, based on a control signal from the main CPU 41.

The card reader 36 reads out data from the smart card and transmits the data to the main CPU 41. Further, the card reader 36 writes data into the smart card based on the control signal output from the main CPU 41. The key switch 38S is mounted to the keypad 38, and outputs a signal to the main CPU 41 in response to an operation of the keypad 38 by the player. The data display 37 displays, based on a control signal from the main CPU 41, the data read by the card reader 36 or the data input by the player through the key pad 38.

The door PCB 80 is connected to a control panel 20, a reverter 21S, a coin counter 21C, and a cold cathode tube 81. The control panel 20 is provided with: a spin switch 23S associated with the spin button 23; a change switch 24S associated with the change button 24; a cashout switch 25S associated with the cashout button 25; a 1-BET switch 26S associated with the 1-BET button 26; and a maximum BET switch 27S associated with the maximum BET button 27. Meantime, the 1-bet switch 26S corresponding to the 1-bet button 26 and the maximum bet switch 27S corresponding to the maximum bet button 27 serve as the bet unit 111 in FIG. 2. Each of the switches 23S to 27S outputs a signal to the main CPU 41, when a player presses the associated one of buttons 23 to 27.

The coin counter 21C is provided within the coin insertion slot 21, and identifies whether the coin inserted into the coin insertion slot 12 by the player is genuine. A coin except the genuine coin is discharged from the coin outlet 19. In addition, the coin counter 21C outputs an input signal to the main CPU 41 upon detection of a genuine coin.

The reverter 21S is operated on the basis of the control signal output from the main CPU 41 and distributes a coin, which is recognized as a genuine coin by the coin counter 21C, to a not-illustrated cash box or hopper 66 mounted in the gaming terminal 10. In other words, when the hopper 66 is full of the coins, the genuine coin is distributed into the cash box by the reverter 21S. On the other hand, when the hopper 66 is not yet full with the coins, the genuine coin is distributed into the hopper 66. The cold cathode tube 81 functions as a backlight mounted to rear sides of the lower image display panel 16 and the upper image display panel 33. This cold cathode tube 81 turns on according to a control signal from the main CPU 41.

(Electrical Structure of Center Controller 200)

FIG. 12 is a block diagram illustrating an electrical structure of the center controller 200. The center controller 200 is provided therein with a control unit. As illustrated in FIG. 12, the control unit includes a motherboard 240, a gaming board 250, an actuator, or the like.

The gaming board 250 has the same structure as that of the gaming board 50. The motherboard 240 has the same structure as that of the motherboard 40.

The motherboard 240 includes a main CPU 241, a ROM 242, and a RAM 243.

The main CPU 241 has functions of performing a sixth process of obtaining one or more JP chances and one or more progressive values from the gaming terminals 10; a seventh

process of accumulatively storing the number of JP chances and progressive values obtained in a later-detailed center JP chance storage unit 225 and a progressive storage unit 226 for each of the gaming terminals 10; a eighth process of running a JP game at a predetermined timing only for a gaming terminal 10 in which the number of JP chances stored in the center JP chance storage unit 225 equals or surpasses a predetermined number; a ninth process of determining a payout according to a result of the JP game; a tenth process of, when the JP game is run, causing a rescue count unit 230 to count the number of JP games run, and when the predetermined number of JP games is run, determining whether a value obtained by subtracting a sum of one or more payouts of the JP game from a sum of one or more progressive values equals or surpasses a predetermined value; and an eleventh process of determining a rescue payout only for a gaming terminal 10 in which the JP game is run and a value obtained by subtracting a sum of one or more payouts of the JP game from a sum of one or more progressive values equals or surpasses a predetermined value. That is, the main CPU 241 serves as a time recorder 228 of FIG. 2, the JP game running unit 224, the shared display control unit 221, the JP game payout determining unit 227, the rescue count unit 230 and the rescue payout determining unit 229.

The ROM 242 stores a program run by the main CPU 241, and permanently-used data.

The RAM 243 stores data or a program used for the main CPU 241 to perform a process. For example, the RAM 243 has the JP game storage unit 223 of FIG. 2, the JP game screen storage unit 222, the center JP chance storage unit 225, and the progressive storage unit 226, in the form of data areas. In the data area of the JP game storage unit 223 is stored data related to a JP game. In the data area of the JP game screen storage unit 222 is stored display information which is based on the data related to the JP game. In the data area of the center JP chance storage unit 225 is stored the JP chance table of FIG. 9. The data area of the progressive storage unit 226 stores therein the payout history data table of FIG. 10.

Further, the center controller 200 includes a graphic board 268 and a drive motor 270 which serve as main actuators.

The graphic board 268 has the same structure as that of the graphic board 68, except in that the graphic board 268 controls image displaying of the shared display 203 based on a control signal from the main CPU 241.

The drive motor 270 is a stepping motor and is connected to a not-illustrated drivewheel. The drive motor 270 is driven by a control signal from the main CPU 241, and rotates the drive wheel to move the shared display 203.

Further, the center controller 200 includes a power unit 245 and a communication interface 244.

The power unit 245 serves as a power source for supplying power to the motherboard 240. The communication interface 244 communicates with the terminal controller 100 provided in each of the gaming terminals 10, through a communication line.

(Operation of Gaming Machine 1: Boot Process)

The following describes a boot process routine which takes place in the gaming machine 1. Upon powering on the gaming machine 1, a boot process shown in FIG. 13 starts in: the mother board 240 and gaming board 250 in the center controller 100, and in the mother board 40 and the gaming board 50 in the terminal controller 100. The memory cards 53 and 263 are assumed to be inserted into the card slots 53S and 263S of the gaming boards 50 and 250, respectively. Further, the GALs 54 and 254 are assumed to be attached to the IC sockets 54S and 254S, respectively.

First, turning on the power switch of (powering on) the power units 45 and 245 boots the motherboards 40 and 240, and the gaming boards 50 and 260. Booting the motherboards 40 and 240 and the gaming boards 50 and 250 starts separate processes in parallel. Specifically, in the gaming board 50 and 250, the CPUs 51 and 251 read out preliminary authentication programs stored in the boot ROMs 52 and 252, respectively. Then, preliminary authentication is performed according to the read out programs so as to confirm and authenticate that no modification is made to authentication programs, before reading them in the motherboards 40 and 240, respectively (S1). Meanwhile, the main CPUs 41 and 241 of the motherboards 40 and 240 run BIOS stored in the ROMs 42 and 242 to load into the RAMs 43 and 243 compressed data built in the BIOS, respectively (S2). Then, the main CPUs 41 and 241 run a procedure of the BIOS according to the data loaded into the RAMs 43 and 243 so as to diagnose and initialize various peripheral devices (S3).

The main CPUs 41 and 241, which are respectively connected to the ROMs 55 and 255 of the gaming boards 50 and 250 via PCI buses, read out authentication programs stored in the ROMs 55 and 255 and stores them in the RAMs 43 and 243 (S4). During this step, the main CPUs 41 and 241 each derives a checksum through ADDSUM method (a standard check function) which is adopted in a standard BIOS, and store the authentication programs into RAMs 43 and 243 while confirming if the operation of storing is carried out without an error.

Next, the main CPUs 41 and 241 each checks what connects to the IDE bus. Then, the main CPUs 41 and 241 access, via the IDE buses, to the memory cards 53 and 253 inserted into the card slots 53S and 253S, and read out game programs and game system programs from the memory cards 53 and 253, respectively. In this case, the CPUs 41 and 241 each reads out four bytes of data constituting the game program and the game system program at one time. Next, with the authentication programs stored in the RAM 43 and 243, the CPUs 41 and 241 authenticate the game program and the game system program read out to confirm and prove that these programs are not modified (S5).

When the authentication properly ends, the main CPUs 41 and 241 write and store the authenticated game programs and game system programs in RAMs 43 and 243 (S6).

Next, the main CPUs 41 and 241 access, via the PCI buses, to the GALs 54 and 254 attached to the IC socket 54S•254S, and read out payout rate setting data from the GALs 54 and 254, respectively. The payout rate setting data read out is then written and stored in the RAMs 43 and 243 (S7).

Next, the main CPUs 41 and 241 read out, via the PCI buses, country identification information stored in the ROMs 55 and 255 of the gaming boards 50 and 255, respectively. The country identification information read out is then stored in the RAMs 43 and 243 (S8).

After this, the main CPU 41 and 241 each performs an initial process of FIG. 14.

(Operation of Gaming Machine 1: Initial Process)

The following describes an initial process which takes place in the gaming machine 1. When the boot process of FIG. 12 is completed, the center controller 200 reads out from the RAM 243 a center side initial setting routine illustrated in FIG. 14 and executes the routine. Meanwhile, when the boot process of FIG. 12 is completed, the gaming terminal 10 reads out from the RAM 43 a terminal side initial setting routine illustrated in FIG. 14 and executes the routine. The center side and terminal side initial setting routines are executed in parallel.

First, the main CPU 41 of the gaming terminal 10 checks operations of a work memory such as RAM 43 (A1). Then, the main CPU 41 determines if all the check results are normal (A2). If the main CPU 41 determines that the check results contain an error (A2: NO), the main CPU 41 outputs a signal notifying the error (hereinafter, error signal) to the center controller 100 (A3). Further, the main CPU 41 reports the error in the form of illuminating the lamp 30 or the like (A4), and then ends the routine.

On the other hand, if the main CPU 41 determines that the check results are all normal (A2: YES), the main CPU 41 checks operations of various sensors (A5). Then, the main CPU 41 determines if all the check results are normal (A6). If the main CPU 41 determines the check results contain an error (A6: NO), the main CPU 41 executes A3.

On the other hand in A6, if the main CPU 41 determines that the check results are all normal (A6: YES), the main CPU 41 checks operations of various drive mechanisms (A7). Then, the main CPU 41 determines if all the check results are normal (A8). If the main CPU 41 determines the check results contain an error (A8: NO), the main CPU 241 executes A3.

On the other hand in A8, if the main CPU 41 determines that the check results are all normal (A8: YES), the main CPU 41 checks operations of various illuminations (A9). Then, the main CPU 41 determines if all the check results are normal (A10). If the main CPU 41 determines the check results contain an error (A10: NO), the main CPU 41 executes A3.

After the checking operations through the steps A1 to A10 for checking operations of various functions, if the main CPU 41 determines the check results are all normal (A10: YES), the main CPU 41 outputs initial setting signal to the center controller 200 (A11). Then, an initial setting signal is waited from the center controller 200 (A12, A13: NO).

The main CPU 241 of the center controller 200 receives signals from each of the terminals 10 (B1). Then, the main CPU 241 determines whether a signal received is an error signal (B2). If the main CPU 241 determines that the signal is an error signal (B2: YES), the main CPU 241 outputs the error signal to a server of a not-illustrated host computer or the like (B3) to report the error (B4), and ends the routine.

On the other hand in B2, if the main CPU 241 determines that the signal is not an error signal (B2: NO), the main CPU 241 determines whether a predetermined time (check time) has elapsed from the time of powering on (B5). If the main CPU 241 determines that the check time has elapsed (B5: YES), B3 is executed. On the other hand, if the main CPU 241 determines that the check time has not yet elapsed (B5: NO), it is determined whether an initial setting signal is received from each of the gaming terminals 10 (B6). If the main CPU 241 determines that an initial setting signal from any one of the gaming terminals 10 is not received (B6: NO), the process returns to B1.

On the other hand, if the main CPU 241 determines that initial setting signals from all the gaming terminals 10 are received (B6: YES), the main CPU 241 checks operations of work memory such as the RAM 243 (B7). Then, the main CPU 241 determines whether all the check results are normal (B8). If the main CPU 241 determines the check results contain an error (B8: NO), the main CPU 241 executes B3.

On the other hand, if the main CPU 241 determines that the check results are all normal (B8: YES), the main CPU 241 checks operations of various sensors (B9). Then, the main CPU 241 determines whether all the check results are normal (B10). If the main CPU 241 determines the check results contain an error (B10: NO), the main CPU 241 executes B3.

On the other hand in B10, if the main CPU 241 determines that the check results are all normal (B10: YES), the main

CPU 241 checks operations of various drive mechanisms (B15). Then, the main CPU 241 determines whether all the check results are normal (B12). If the main CPU 241 determines the check results contain an error (B12: NO), the main CPU 241 executes B3.

On the other hand in B12, if the main CPU 241 determines that the check results are all normal (B12: YES), the main CPU 241 checks operations of various illuminations (B13). Then, the main CPU 241 determines whether all the check results are normal (B14). If the main CPU 241 determines the check results contain an error (B14: NO), the main CPU 241 executes B3.

After the checking operations through the steps B7 to B14, if the main CPU 241 determines in B14 that all the check results are normal (B14: YES), the main CPU 241 outputs an initial setting signal to all the gaming terminals 10 (B15), and causes the shared display 203 to display a demo-screen (B16). Then, the main CPU 241 ends the routine.

In A12, the main CPU 41 of each of the gaming terminals 10 determines that an initial setting signal is received from the center controller 200 (A13: YES), and causes the terminal display 101 to display a demo-screen (A14). The main CPU 41 then ends the routine.

(Operation of Gaming Terminal 10: Game Running Process Routine)

After the terminal side initial setting routine of FIG. 14, the main CPU 41 of the gaming terminal 10 performs a game running process routine of FIG. 15. Through this game running process routine, a game is run.

As illustrated in FIG. 15, in the game running process routine, whether or not a JP game start signal is received from the center controller 200 is determined (C1). In C1, if it is determined that no JP game start signal is received (C1: NO), whether a coin is bet or not is determined (C2). In this step, it is determined whether a signal from the 1-BET switch 26S entered by pressing of the 1-BET button 26 is received. Meanwhile, it is determined whether a signal from the maximum BET switch 27S entered by pressing of the maximum BET button 27 is received. If no coin is BET (C2: NO), C2 is repeated until a coin is bet.

On the other hand, if a coin is bet (C2: YES), the credit value stored in the RAM 43 is reduced according to the number of coins bet (C3). When the number of coins bet surpasses the number of coins equivalent to the credit value stored in the RAM 43, C4 is repeated without the reduction of the credit value. When the number of coins bet exceeds the maximum number of coins bettable in one game (50 pieces in this embodiment), the process goes to a later-detailed step C4 without the reduction of the credit value.

Then, it is determined whether a spin button 23 is pressed or not (C4). If the spin button 23 is not pressed (C4: NO), the process returns to C2. Here, if the spin button 23 is not pressed (for example, the spin button 23 is not pressed but a command to end the game is input), the reduction of the credit value in C3 is canceled.

On the other hand, when the spin button 23 is pressed (C4: YES), a progressive transmission process is executed (C5). In other words, a progressive signal indicating a part of the game value bet is transmitted to the center controller 200.

Next executed is a base symbol determining process (C6). That is, the stop symbol determining program stored in the RAM 43 is run to determine base symbols 180 to be stopped in the matrix 156. Through the steps is determined a combination of base symbols 180 to be stopped in the matrix 156.

Next executed is a JP symbol determining process (C7). That is, the stop symbol determining program stored in the RAM 43 is run to determine base symbols 180J to be stopped

in the matrix 156. Through the steps is determined a combination of JP symbols 180J to be stopped in the matrix 156.

Then, the scrolling process is executed to scroll base symbols 180 and JP symbols 180J at the same time, on the terminal display 101 (C8). The scrolling process is a process in which the base symbols 180 and the JP symbols 180J respectively determined in C6 and C7 are stopped (rearranged) in the matrix 156 after scrolling of symbols 180 and JP symbols 180J in an upward/downward direction.

10 Next, there is determined whether JP symbols 180J rearranged in the matrix 156 form a chance winning combination (C8). If a chance winning combination is not formed (C9: NO), there is determined whether base symbols 180 rearranged in the matrix 156 form a winning combination (C12).

15 On the other hand in C9, if it is determined that a chance winning combination is formed (C9: YES), a JP chance signal is transmitted to the center controller 200 (C10). After C10, the number of JP chances is added to the number of JP chances in RAM 43 (C11). In this step, the accumulated total 20 of the JP chances is displayed in the JP chance display area 160 of the terminal display 101.

25 Next, if it is determined that a winning combination is formed (C12: YES), a payout according to the winning combination formed is determined (C13). After the payout is determined, a pay out process is executed (C14). On the other hand in C12, if it is determined that no winning combination is formed (C12: NO), this routine is ended.

If a JP game start signal is received from the center controller 200 (C1: YES), a JP game is displayed on the terminal display 101 (C15).

30 After the terminal display 101 displays thereon the JP game in C15, there is determined whether a JP game payout signal is received from the center controller 200 (C16). When it is determined that no JP game payout signal is received 35 (C16: NO), it is determined whether a rescue payout signal is received from the center controller 200 (C18). The rescue payout signal is a signal including the information about a rescue payout that is determined by the center controller 200 when a value obtained by subtracting a sum of payouts of the 40 JP game from a sum of progressive values based on coins inserted from the 1-bet button 26 and the maximum bet button 27 equals or surpasses a predetermined value.

On the other hand, if it is determined that a JP game payout signal is received from the center controller 200 (C16: YES), a payout based on the JP game payout signal is awarded (C17). C18 is executed thereafter.

When it is determined in C18 that a rescue payout signal is not received (C18: NO), it is determined whether a JP game end signal is received or not (C20).

50 On the other hand, when it is determined in C18 that a rescue payout signal is received from the center controller 200 (C18: YES), a rescue payout based on the rescue payout signal is awarded (C19). C20 is executed thereafter.

When it is determined in C20 that no JP game end signal is 55 received (C20: NO), a JP game end signal is waited (C20).

On the other hand, when it is determined in C20 that a JP game end signal is received from the center controller 200 (C20: YES), the number of JP chances stored in the RAM 43 is initialized (C21). In this step, the number of JP chances displayed on the JP chance display area of the terminal display 101 is also set to the initial value. This routine ends thereafter.

60 Through the game running process routine, the gaming terminal 10 runs a base game, and at the same time, runs a chance game offering a chance of winning a JP chance which qualifies a player to join a JP game offering a chance of winning a higher payout than the base game. Then, the player

is awarded a payout according the result of the base game, and is given zero or more chance flags according to the result of the chance game. Further, the number of JP chances awarded is accumulatively stored in the RAM 43 of the gaming terminal 10. When this number equals or surpasses a predetermined number, the JP game is run. According to the result of the JP game is awarded a payout. This structure allows a player to play the chance game while he/she plays the base game, and allows the player to obtain zero or more JP chances which are given according to a result of the chance game. Accordingly, the player is able to know the result of the chance game while enjoying the base game. This realizes a higher level of gaming characteristic than a gaming machine which independently runs a chance game inside the gaming terminal 10 where a player is not able to see. In addition, a rescue payout, which is determined when a value obtained by subtracting a sum of payouts of the JP game from a sum of progressive values based on coins inserted from the 1-bet button 26 and the maximum bet button 27 equals or surpasses a predetermined value, is awarded to a player. Hence, even when a sum of payouts of the JP game is small, a rescue payout may be awarded. Accordingly, it is possible to enable a player to have expectations for a rescue payout.

(Operation of Center Controller 200: Progressive Addition Process Routine)

FIG. 16 is a diagram illustrating a progressive addition process routine that is executed in the center controller 200. When the progressive addition process is executed, the center controller 200 determines whether a progressive signal from a terminal controller 100 of a gaming terminal 10 is received (D1). If the center controller 200 determines that no progressive signal is received (D1:NO), the center controller 200 waits for a progressive signal (D1).

On the other hand, if the center controller 200 determines that a progressive signal is received from a terminal controller 100 (D1:YES), the center controller 200 accumulatively stores a progressive value indicated by the progressive signal in the RAM 243 (D2). Meantime, the obtained progressive values are stored and updated in the “accumulatively inserted bet amount” of the payout history data table (refer to FIG. 10) provided in the RAM 243 for each gaming terminal 10. This routine ends thereafter.

(Operation of Center Controller 200: JP Chance Addition Process Routine)

FIG. 17 is a diagram indicating a JP chance addition process routine that is executed in the center controller 200. When the JP chance addition process routine is executed, the center controller 200 determines whether a JP chance signal is received from the terminal controller 100 of a gaming terminal 10 (E1). If the center controller 200 determines that no JP chance signal is received (E1: NO), the center controller waits for the JP chance signal (E1).

On the other hand, if the center controller 200 determines that a JP chance signal is received from the terminal controller 100 (E1:YES), the center controller records the time of obtaining the JP chance (E2).

After E2, the center controller 200 determines, based on the JP chance signal, the terminal number given to the gaming terminal 10 having transmitted the JP chance signal received (E3). Then, a set of data containing “time” recorded in E2, “terminal number” determined in E3, and “the number of JP chances” indicated by the JP chance signal are stored in the RAM 243 and are updated (E4). This routine ends thereafter.

(Operation of Center Controller 200: JP Game Running Process Routine)

FIG. 18 is a diagram illustrating a JP game running process routine that is executed in the center controller 200. When the

JP game running process routine is executed, the center controller 200 determines whether a JP game starting time has come (F1). If the center controller 200 determines the JP game starting time has not come, the JP game starting time is waited (F1).

On the other hand in F1, if the center controller 200 determines the JP game starting time has come (F1:YES), the center controller 200 determines if there is a gaming terminal 10 to participate in the JP game, by referring to the JP chance data table stored in RAM 243 (F2). If the center controller 200 determines that there is no gaming terminal 10 to participate in the JP game (F2:NO), the center controller 200 waits for the next JP game starting time (F3). The process then returns to F1.

On the other hand in F2, if there is a gaming terminal 10 to participate in the JP game (F2:YES), the center controller 200 determines the terminal number of the gaming terminal 10 (F4). Then, a JP game start signal is transmitted to the terminal controller 100 provided in the gaming terminal 10 whose terminal number has been determined in F4 (F5). This transmission of the JP game start signal in F5 triggers the JP game to start (F6).

When the JP game starts in F6, there is determined a gaming terminal 10 to be subjected to a process of determining whether or not a jackpot is awarded. (F7). The order of subjecting gaming terminals 10 to the process of determining is determined by referring to the JP chance data table in the RAM 243 so that the JP chances having obtained are sequentially consumed in order of time of obtaining the JP chances. Then, a process of determining whether or not a jackpot is awarded is performed with respect to a gaming terminal 10 with the terminal number determined in F7 (F8). If it is determined that a jackpot will not be awarded (F8:NO), the number of JP chances obtained by the gaming terminal 10 with the determined terminal number, which number is stored in the RAM 243, is reduced by “1” (F12).

On the other hand, if it is determined that a jackpot will be awarded (F8:YES), an amount of the payout of the JP game is determined (F9). After F9, a JP game payout signal is transmitted to the terminal controller 100 of the gaming terminal with the determined terminal number (F10). Then, the payout amount of the JP game determined in F9 is stored and updated in the “accumulated JP payout amount” of the payout history data table (refer to FIG. 10) provided in the RAM 243 for each gaming terminal 10 (F11). After F11 is played F12.

After F12, there is determined whether JP chances of all the gaming terminals 10 stored in the RAM 243 are consumed (F13). If it is determined that there is a JP chance yet to be consumed (F13: NO), the process returns to F7.

On the other hand, when it is determined in F13 that the JP chances of all the gaming terminals 10 are consumed (F13: YES), one is subtracted from the number of JP games. (F14). Afterwards, a process of F15 is executed.

Then, it is determined whether all of the number of JP games subtracted are consumed. That is, in the present embodiment, it is determined whether five times of JP games are consumed or not (F15). On the other hand, when it is determined that all JP chances are not consumed (F15: NO), a JP game end signal is transmitted to the terminal controller 100 of the gaming terminal 10 that has transmitted a JP game start signal (F21). This routine ends thereafter.

On the other hand, when it is determined in F15 that 5 times of JP game are consumed (F15: YES), it is determined whether the “subtraction amount” of the sums in the payout history data table equals or surpasses a predetermined value.

When it is determined that the "subtraction amount" is less than a predetermined value (F16: NO), a process of F21 is executed.

On the other hand, when it is determined that the "subtraction amount" equals or surpasses a predetermined value (F16: YES), a rescue payout is determined (F17). At this time, a rescue payout is determined only for the gaming terminal 10 in which the "subtraction amount" of each gaming terminal 10 in the payout history data table equals or surpasses a predetermined value. On the other hand, when there is no gaming terminal 10 in which the "subtraction amount" equals or surpasses a predetermined value, a rescue payout is determined for all the gaming terminals 10.

Then, a rescue payout signal based on the rescue payout is transmitted to the gaming terminal 10 determined in F17 (F18). Then, an amount as the awarded rescue payout is subtracted from the "accumulatively inserted bet amount" of the payout history data table in the gaming terminal 10 to which the rescue payout is awarded (F19). Afterwards, the number of JP game is re-set to 5 times (F20), a process of F21 is executed and then this routine ends.

Like the JP game running process routine, the progressive values obtained from the gaming terminals 10 are accumulatively stored in the payout history data table of FIG. 10 of the RAM 243. Then, it is determined whether a value obtained by subtracting a sum of one or more payouts of the JP game from a sum of one or more progressive values stored equals or surpasses a predetermined value. A rescue payout is determined and awarded to a player only for the gaming terminal 10 in which the value equals or surpasses a predetermined value. Hence, even when a sum of payouts of the JP game is small, a rescue payout may be awarded. Accordingly, it is possible to enable a player to have expectations of a rescue payout.

Note that the present embodiment deals with a case where the JP game is run for a gaming terminal 10 having one JP chance; however, the present invention is not limited to this. For example, the JP game may be run for a gaming terminal 10 having three JP chances.

Further, the present embodiment deals with a case where one JP chance is awarded for a chance winning when three JP symbols 180J are arranged in the matrix 156; however, the present invention is not limited to this. For example, two JP chances may be awarded when three JP symbols 180J are arranged in the matrix 156.

Further, the present embodiment deals with a case where the number of JP chances obtained by a gaming terminal 10 is displayed on the terminal display of the gaming terminal 10; however, the present invention is not limited to this. For example, it is possible to collectively display the numbers of obtained JP chances of all the gaming terminals 10 on the shared display 203.

Further, in the present embodiment, when 5 times of the JP game are consumed, it is determined whether a rescue payout is awarded or not. However, the present invention is not limited thereto. For example, it may be possible that when 10 times of the JP game are consumed, it is determined whether a rescue payout is awarded or not.

The detailed description of the present invention provided hereinabove mainly focused on characteristics thereof for the purpose of easier understanding; however, the scope of the present invention shall be construed as broadly as possible, encompassing various forms of other possible embodiments, and therefore the present invention shall not be limited to the above description. Further, the terms and phraseology used in the present specification are adopted solely to provide specific illustration of the present invention, and in no case

should the scope of the present invention be limited by such terms and phraseology. Further, it will be obvious for those skilled in the art that the other structures, systems, methods or the like are possible, within the spirit of the invention described in the present specification. The description of claims therefore shall encompass structures equivalent to the present invention, unless otherwise such structures are regarded as to depart from the spirit and scope of the present invention. Further, the abstract is provided to allow, through a simple investigation, quick analysis of the technical features and essences of the present invention by an intellectual property office, a general public institution, or one skilled in the art who is not fully familiarized with patent and legal or professional terminology. It is therefore not an intention of the abstract to limit the scope of the present invention which shall be construed on the basis of the description of the claims. To fully understand the object and effects of the present invention, it is strongly encouraged to sufficiently refer to disclosures of documents already made available.

The detailed description of the present invention provided hereinabove includes a process executed on a computer or computer network. The above descriptions and expressions are provided to allow the one skilled in the art to most efficiently understand the present invention. A process performed in or by respective steps yielding one result or blocks with a predetermined processing function described in the present specification shall be understood as a process with no self-contradiction. Further, the electrical or magnetic signal is transmitted/received and written in the respective steps or blocks. It should be noted that such a signal is expressed in the form of bit, value, symbol, text, terms, number, or the like solely for the sake of convenience. Although the present specification occasionally personifies the processes performed in the steps or blocks, these processes are essentially executed by various devices. Further, the other structures necessary for the steps or blocks are obvious from the above descriptions.

What is claimed is:

1. A gaming device, comprising:
a plurality of gaming terminals, each of the gaming terminals configured to run a base game and a chance game at the same time, to determine and award a payout according to a result of the base game, to determine a number of chance flags to be awarded according to a result of the chance game, and to award the determined one or more chance flags and output a chance signal;
a special game offering a chance of winning a higher payout than the base game, which offers a chance of winning a payout according to a predetermined combination;
a center storage unit configured to store the number of one or more chance flags awarded in each of the gaming terminals and to store a time of obtaining the one or more chance flags based on the chance signal from each of the gaming terminals, each of the chance flags qualifying a player to join the special game;
a shared display which displays an image of the special game; and
a center controller which performs the steps of:
(b1) obtaining the number of chance flags from each of the gaming terminals;
(b2) accumulatively storing the number of the one or more chance flags and that are obtained from each of the gaming terminals in the center storage unit;
(b3) associating the time of obtaining the one or more chance flags with the number of the one or more chance flags;

35

- (b4) running the special game at a predetermined timing, when the number of chance flags of at least one gaming terminal stored in the center storage unit equals or surpasses a first predetermined number;
- (b5) determining whether a jackpot is established for a single chance flag in the special game each time the single chance flag is sequentially consumed from among all chance flags of gaming terminals running the special game, wherein the chance flags are sequentially consumed in order of a time of obtaining each of the chance flags; and
- (b6) determining a regular payout of each of the gaming terminals participating in the special game according to a result of repeating the (b5) step.
2. The gaming device according to claim 1, wherein the center controller further performs the steps of:
- (b7) obtaining game values betted in each of the gaming terminals from each of the gaming terminals;
- (b8) accumulatively storing the game values obtained from each of the gaming terminals in the center storage unit;
- (b9) determining whether a subtraction amount obtained by subtracting a sum of one or more regular payouts of the special game from a sum of one or more game values equals or surpasses a predetermined value; and
- (b10) determining a special payout when the subtraction amount equals or surpasses a predetermined value.
3. The gaming device according to claim 2, further comprising
- a count unit that counts the number of special games run, wherein when the special game is run, the center controller causes the count unit to count the number of special games, when the number of special games reaches a second predetermined number, the center controller determines whether the subtraction amount equals or surpasses the predetermined value.
4. The gaming device according to claim 2, wherein the center controller accumulatively stores the number of chance flags in the center storage unit for each of the gaming terminals; runs the special game at the predetermined timing only for a gaming terminal in which the number of chance flags equals or surpasses the first predetermined number; and determines the special payout only for the gaming terminal that runs the special game.
5. The gaming device according to claim 2, wherein the controller accumulatively stores the one or more game values and the number of chance flags in the center storage unit for each of the gaming terminals; runs the special game at the predetermined timing only for a gaming terminal in which the number of chance flags equals or surpasses the first predetermined number; and determines the special payout only for the gaming terminal in which the special game is run when the subtraction amount equals or surpasses the predetermined value.
6. The gaming device according to claim 2, further comprising
- a count unit that counts the number of special games run, wherein the center controller accumulatively stores the number of chance flags and the game values in the center storage unit for each of the gaming terminals; runs the special game at the predetermined timing only for the gaming terminal in which the number of chance flags equals or surpasses the first predetermined number; when the special game is run, causes the count unit to count the number of special games; when the number of special games reaches a second predetermined number,

36

- determines whether the subtraction amount equals or surpasses the predetermined value; and determines the special payout only for the gaming terminal in which the special game is run when the subtraction amount equals or surpasses the predetermined value.
7. The gaming device according to claim 1, wherein each gaming terminal awards the payout when a predetermined combination of base symbols are arranged in a pay line in the base game, and awards the one or more chance flags when at least a predetermined number of scatter symbols are arranged irrespective of the pay line in the chance game.
8. A playing method of a gaming device, wherein the gaming device includes a plurality of gaming terminals, a center storage unit and a center controller, and each of the gaming terminals is configured to run a base game and a chance game at the same time, to determine and award a payout according to a result of the base game, to determine a number of chance flags to be awarded according to a result of the chance game, and to award the determined one or more chance flags and output a chance signal, each of the chance flags qualifying a player to join the special game, the playing method comprising:
- (c1) obtaining, by the center controller, the number of chance flags from each of the gaming terminals;
- (c2) accumulatively storing, by the center controller, the number of the one or more chance flags that are obtained from each of the gaming terminals in the center storage unit;
- (c3) associating, by the center controller, a time of obtaining the one or more chance flags with the number of the one or more chance flags, the time of obtaining the one or more chance flags being determined based on the chance signal from each of the gaming terminals;
- (c4) running, by the center controller, a special game at a predetermined timing, when the number of chance flags of at least one gaming terminal stored in the center storage unit equals or surpasses a first predetermined number, the special game offering a chance of winning a higher payout than the base game;
- (c5) determining, by the center controller, whether a jackpot is established for a single chance flag in the special game each time the single chance flag is sequentially consumed from among all chance flags of gaming terminals running the special game, wherein the chance flags are sequentially consumed in order of a time of obtaining each of the chance flags; and
- (c6) determining, by the center controller, a regular payout of each of the gaming terminals participating in the special game according to a result of repeating the (c5) step.
9. The playing method according to claim 8, further comprising:
- (c7) obtaining, by the center controller, game values betted in each of the gaming terminals from each of the gaming terminals;
- (c8) accumulatively storing, by the center controller, the game values obtained from each of the gaming terminals in the center storage unit;
- (c9) determining, by the center controller, whether a subtraction amount obtained by subtracting a sum of one or more regular payouts of the special game from a sum of one or more game values equals or surpasses a predetermined value; and

37

(c10) determining, by the center controller, a special payout when the subtraction amount equals or surpasses a predetermined value.

10. The playing method according to claim **8**, wherein each gaming terminal awards the payout when a predetermined combination of base symbols are arranged in a

38

pay line in the base game, and awards the one or more chance flags when at least a predetermined number of scatter symbols are arranged irrespective of the pay line in the chance game.
